Clearite Products, Inc., New York, N. Y.

Application May 18, 1945, Serial No. 119,609

Term of patent 3½ years

(Cl. D85—2)

To all whom it may concern:

Be it known that I, Monroe B. Toklas, a citizen of the United States of America, residing in New York city, county of New York, and State of New York, have invented a new, original, and ornamental Design for a Cigarette Dispenser or the like, of which the following is a specification, reference being had to the accompanying drawing, forming part thereof, wherein,

Figure 1 is a front elevational view of a cigarette dispenser or the like, showing my new design.

Figure 2 is a side elevational view.
Figure 3 is a rear elevational view, and
Figure 4 is a front perspective view showing
the cigarette dispenser or the like in open position.

I claim:

The ornamental design for a cigarette dispenser or the like, substantially as shown.

MONROE B. TOKLAS.
